US00D894184S

(12) **United States Design Patent** (10) Patent No.: **US D894,184 S**
 Wang et al. (45) Date of Patent: **** Aug. 25, 2020**

(54) **KEYBOARD**

(71) Applicant: **COMPAL INFORMATION (KUNSHAN) CO., LTD**, Kunshan, Jiangsu (CN)

(72) Inventors: **Du-Ying Wang**, Jiangsu (CN); **Chang-Sheng Zhang**, Jiangsu (CN)

(73) Assignee: **COMPAL INFORMATION (KUNSHAN) CO., LTD**, Kunshan (CN)

(**) Term: **15 Years**

(21) Appl. No.: **29/667,801**

(22) Filed: **Oct. 24, 2018**

(30) **Foreign Application Priority Data**

May 18, 2018 (TW) 107302780

(51) LOC (12) Cl. **14-02**

(52) U.S. Cl.

USPC **D14/391**

(57) **CLAIM**

We claim the ornamental design for a keyboard, as shown and described.

DESCRIPTION

FIG. 1 is a perspective view of a keyboard, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The portions of the keyboard shown in broken lines from no part of the claimed design.

1 Claim, 7 Drawing Sheets
